X-RAY DENTAL FILM PACKAGE

Millard B. Hodgson, Chicago, Ill., assignor to
Eastman Kodak Company, Rochester, N. Y., a
corporation of New York

Application January 23, 1931, Serial No. 510,646

4 Claims. (Cl. 250—34)

This invention relates to packages of sensitized film prepared for use individually in dental X-ray work.

The invention is for use with X-ray dental film packages of the type described in Patent Number 1,293,323 of February 4, 1919, to Buck, Number 1,441,160 of January 2, 1923, to Lovejoy, and 1,437,827 of December 5, 1922, to Sulzer and Dewey.

An object of the invention is to produce a film package of the general kind described in the patents mentioned which may be used with greater comfort to the patient. This is attained by providing a cushion which eliminates the sharp edges of the packet.

This object is further attained by providing an absorbent backing which allows the film package to be held in place with greater security and greater comfort.

Reference to the drawing will more clearly illustrate the invention.

Figure 1 is a view from the back of the finished film package.

Figure 2 is a cross-section of the package made on the line 2—2 of Figure 1.

Figure 3 is a side view showing the absorbent backing partly detached.

In one embodiment of my invention I take an X-ray dental film package of the type described in the patents mentioned and secure to one face of this package a layer or pad of an absorbent material. This pad, for example, may consist of one or more layers of pressed absorbent cotton. Such an absorbent material is found on the market under the name of "Cottonoid". This material consists of several layers of absorbent cotton which have been pressed into thin sheets and laid one on the other. Any other material suitably absorbent and resilient may, of course, be used. This pad is cut to a size slightly greater than that of the film package. It will usually be sufficient to have this pad extend beyond the edge of the film envelop by $\frac{1}{4}$ to $\frac{3}{2}$ of an inch. I fasten this pad by a light suitable adhesive to the exterior of the film envelop on one face, in such a way that it can be easily torn away. While it may be described as being detachable, it is understood, of course, that on tearing it away a portion of the layer immediately attached to the envelop may be left behind as indicated at 10 in Fig. 3, though this is of no importance and will do no harm.

The structure of the finished package is more readily understood by reference to the drawing, wherein like characters designate the same parts

throughout. The finished product according to my invention is shown in cross section in Fig. 2 in which I take an X-ray dental film package of the type described which consists of an envelop 7 surrounding a film strip 5 and a lead foil backing 6 and sealed by a paper strip 8 and having attached to the face of the envelop the absorbent pad 9. It will be noted that the edges 3 of the pad 9 project beyond the edges of the envelop of the film package 4 to a sufficient extent to 10 form a soft pad over the more or less sharp edges of the envelop. In Fig. 1 the edges 3 of the pad are again seen extending beyond the edges of the package or envelope 4. Fig. 3 shows the pad 9 partially detached from the film envelop 4 at one 15 edge.

X-ray dental film packages made in accordance with my invention possess marked advantages and increased comfort for the patient. The absorbent backing extends over the sharp 20 edges of the film envelop, thereby preventing the sharp edges from coming in contact with the mouth. The pad 9 having excellent absorbent qualities prevents the discomfort caused by an excessive flow of saliva and consequent slipping of the package.

The attached pad may be made of sterilized or antiseptic cotton which makes the package more sanitary. The pad may, if desired, be treated with a pleasant tasting antiseptic.

The package also has advantages from the standpoint of the operator, as the pads can be quickly torn off as soon as removed from the patient's mouth, the envelop being then stored, if desired, for development. There is no danger 35 from light leak when the pad is torn off.

I consider as included within my invention all modifications and equivalents coming within the scope of the appended claims.

What I claim is:

1. An X-ray dental film package comprising an envelop and a film therein, said envelop having detachably secured to it a layer of saliva, absorbent material extending beyond the edges of said envelop.

2. An X-ray dental film package comprising an envelop and a film therein, one face of said envelop having detachably secured to it, a layer of saliva, absorbent material of uniform thickness and dimensions greater than that of the envelop, so as to cause the saliva, absorbent layer to cover the entire face and extend over the edge of said envelop.

3. An X-ray dental film package comprising an envelop and a film therein, the face of said

envelop having detachably secured to it by suitable adhesive, a pad of absorbent cotton in the form of pressed layers, the edges of the pad extending beyond the edges of the envelop.

5 4. An X-ray dental film package comprising a closed flat envelope and a film therein, there be-

ing adhesively secured to one flat surface of said envelope a pad of absorbent cotton in the form of pressed layers, said pad covering uniformly said surface and extending beyond the edges of the envelope.

MILLARD B. HODGSON.
